PULL TAB FOR A TEAR STRIP OPENER

Nick S. Khouri and David F. Brasel, Worth, Ill., assignors to Continental Can Company, Inc., New York, N.Y., a corporation of New York

Filed Mar. 28, 1968, Ser. No. 11,176

Term of patent 14 years

Int. Cl. D9—02

U.S. Cl. D9—256

FIG. 1 is a top plan view of a pull tab for a tear strip opener, showing our new design;

FIG. 2 is a bottom plan view thereof;

FIG. 3 is a side elevational view thereof;

FIG. 4 is a rear elevational view thereof taken from the left of FIG. 3; and

FIG. 5 is a front elevational view thereof taken from the right of FIG. 3.

The characteristic feature of our design resides in the presence of two spaced-apart indentations in the ring portion of the pull tab as shown.

We claim:

The ornamental design for a pull tab for a tear strip opener, as shown and described.
